UNITED STATES PATENT OFFICE.

ALBERT J. LOEPSINGER, OF PROVIDENCE, RHODE ISLAND, ASSIGNOR TO GENERAL FIRE EXTINGUISHER COMPANY, A CORPORATION OF NEW YORK.

SPRINKLER SYSTEM.

Application filed October 14, 1922. Serial No. 594,473.

To all whom it may concern:

Be it known that I, ALBERT J. LOEPSINGER, a citizen of the United States, residing at Providence, in the county of Providence and 5 State of Rhode Island, have invented certain new and useful Improvements in Sprinkler Systems; of which the following is a specification.

This invention relates to improvements in 10 sprinkler systems for fire extinguishing apparatus. More particularly it relates to sprinkler systems adapted to distribute and automatically to discharge a fire extinguishing agent, for which water is herein used as 15 a type. The invention is herein described and illustrated as it has been developed for application on shipboard and in similar places where the automatic sprinkler systems hitherto known are objectionable because of the danger of the system being set 20 into operation, or made to leak with damaging results, by a sprinkler head somewhere in the system being knocked off or distorted. In sprinkler systems as at present constituted, the distribution system is filled, either 25 with water or with air; and in case of accidental damage to the sprinkler head, the water flows out instantly if it be a wet system; or, if it be a dry system, the air flows 30 out, and in due process of time reduces the pressure so that the dry pipe valve trips and water flows out, in either case with possibility of doing considerable damage to 35 cargo; but no way has been known to avoid this in an automatic system without introducing an equal or greater danger; and so 40 it has been customary to have a parallel system of thermostats which notify the engineer, who then by hand turns water into the particular branch line where the fire is. Obviously such a system, which depends on 45 the action of an intermediary electrical system and a thermostat and the hand operated supply from some central point after the signal of the thermostat has been received, is lacking in many of the advantages of an 50 automatic sprinkler system.

It is the object of the present invention 55 to provide a completely automatic sprinkler system which will unfailingly operate in case of a fire in the region of a sprinkler head, but which will not operate if the sprinkler head is accidentally opened as by a blow which 60 knocks the head off of the system or seri-

ously distorts it, and which will not leak 55 with damaging results even in the case of such an accident. Although developed with this purpose particularly in mind, the apparatus involved is suitable in other connections, so that the patent is not to be limited 60 to this particular use, except as limitations in the appended claims require, and it is intended that the patent shall cover by suitable expression in the appended claims whatever features of patentable novelty exist 65 in the invention disclosed.

The objects of the invention are accomplished by providing a dry pipe system having a valve separating the supply of water or other fire extinguishing agent from the 70 distribution system. The valve is illustrated as being of the differential type, although it is not necessarily so. Among valves of that type it is novel in that the pressure of the supply of water holds the valve closed, 75 being communicated through a restricted passage to an auxiliary body of water pressing on the large or differential clapper, so long as conditions are set ready for action; and in that its intermediate chamber is open 80 to the distribution system; and in that the latter is filled with air, normally at a low pressure, which may fall to any degree, as by the knocking off of a sprinkler head, without tripping the valve. Sprinkler heads 85 of a peculiar type are provided, in which the jet when discharging normally strikes a target whereby an impulse is communicated to and actuates the dry pipe valve. The invention comprises a suitable actuator of 90 novel type, by which the fluid pressure on the differential clapper is suddenly released, by the opening of a drain therefrom greater than the restricted opening thereinto from the supply. Thereupon the valve opens because the direct pressure of the supply on the valve clapper of the valve is no longer overbalanced. The system comprises a double dry pipe line, one line being for distribution and containing air at low pressure; the other line being small tubing for 100 valve actuation, and containing air at atmospheric pressure; and both being closed but adapted automatically to open in case of a fire at the sprinkler head, while remaining closed elsewhere; and adapted not to open in such a manner as to transmit a 105 valve actuating impulse except in case of fire.

To this end the actuating portion of the apparatus is automatically selective, as in case of leakage from the opening or breaking off of the sprinkler head, and is not operated by any but a normal opening of the sprinkler head with the fluid jet discharge thereof aimed to hit the cooperating opening as a target. This target opening may be located in the yoke of the sprinkler which may be tubular to form a part of the valve actuating system. In case of leakage or removal of a head by accident, air in the pipes flows out harmlessly, but the water supply valve remains closed. An ordinary pressure indicator, with alarm if desired, gives immediate notice.

In the accompanying drawings:

Figure 1 is a side elevation partly in section of fragments of a sprinkler system embodying the invention;

Figure 2 is a detail showing in elevation and in medial section the dry pipe valve of Figure 1;

Figure 3 is a side elevation in medial section through one of the automatic sprinklers on a large scale; and

Figure 4 is an end elevation of a part of the same in medial section.

Referring to the drawings, 10 indicates a pipe leading from a supply of water under pressure into the casing 11 of a dry pipe valve, which in turn is connected with a casing 12, containing apparatus for actuating the dry pipe valve, and with the water distribution system 13 leading to automatic sprinklers, one of which is shown at 14. Auxiliary to this is a system of small diameter piping 15 leading from the sprinklers back to the actuator for tripping the dry pipe valve. The dry pipe valve, which may be of any suitable type, is herein illustrated as being a differential valve of well known type which is particularly well adapted for combination with the other elements of the system. This is represented as being made with a water clapper 21 and another clapper 22 herein called the differential clapper, having separate seats, between which is an intermediate chamber 25 which in the present instance is permanently connected with the distribution system 13 and has a discharge orifice thereto large enough to convey the full flow of water thereto. The differential clapper occupies the general position and arrangement of the air clapper in differential valves previously known, and as illustrated is designed of such diameter and with such leverage that it maintains the water clapper closed whenever the unbalanced closing pressure on it is one-half or more than half of the unbalanced opening pressure on the water clapper. If there were no pressure in the intermediate chamber 25, this would mean that a ratio of 2 to 1 for pressure in the water space 23 to pressure

in the differential space 24 must exist before the valve would open.

When set for normal operation, this intermediate space 25 contains air under a low pressure, say for example, ten pounds, which extends through the distribution system 13 which also is filled with air. The water side 23 of the clapper 21 has water at whatever pressure is provided, for example, at sixty pounds per square inch, and the other side of the differential 24 contains water at the same pressure, which is supplied and maintained by a by-pass connection 27. A connection 28 from the differential valve chamber 24 to the actuator chamber 12 permits the same pressure to extend into the actuator chamber. The by-pass 27 contains a restriction 29 which may take any convenient form, and which is illustrated as a section set in the middle of the pipe 27 having a passage which may, for example, be $1/8$ " in diameter.

Within the actuator is the entrance 30 of a drain, preferably into the intermediate chamber 25 although, if desired, it may vent to atmosphere, of considerably larger diameter than the restriction 29, for example, $1/4$ " to $1/2$ ", which is normally held closed by a valve pivoted at 34, and having projecting end 35 in position to be hit and tripped by the short end of a lever 36 whose long end 38 is heavily weighted and is held raised by a latch 40 in such position that when the latch is released the weight 38 falls, throwing up the short end 36 of the lever, and thus knocking open the valve 32 and so opening a drain to atmosphere or other region of lower pressure for the contents of the chamber. By reason of the greater size of the drain 30, the pressure on the restraining side of the dry pipe valve, to-wit: in chambers 24 and 12, will fall rapidly when the drain 30 is opened, the fall being practically instantaneous if these chambers are filled with water which is incompressible, and approximating instantaneity if they are filled with air, or partly with air. When such a fall occurs, the pressure in chamber 24, which has been operating to restrain the opening of water clapper 21, and which will restrain it under the 1 to 1 conditions assumed, and so long as it remains at least half as great as the water pressure, immediately falls to less than half, so that the valve 21, 22 swings open. This action is aided, of course, by the air pressure in the distribution system acting in space 25, which acts differentially to help open the valve.

The distribution system may be of any suitable arrangement provided at intervals with automatic sprinklers 14. The sprinkler illustrated in detail in Figures 3 and 4 has features of a well known type in which the water or air seeking to escape from the interior 50 of its base is restrained

by a diaphragm 51 and a valve 52 closing a central hole through the diaphragm, said valve being held by a fusible strut connection 53 based on a yoke 54 which carries 5 the usual water spreader 55. The yoke 54 is tubular, as seen at 54' in Figures 3 and 4 and is arranged at its ends 56 for connection with the auxiliary piping system 15, which system is continuous through the 10 tube of the yoke 54 and has an opening 58 on the interior of the yoke at the crest thereof and facing toward the discharge passage 50 of the sprinkler base. These parts are so related that a fluid issuing in 15 jet form from the base 50 of the sprinkler, the valve and diaphragm and the strut being cleared away, will strike into the opening 58; and thus the fluid issuing from the sprinkler is projected in greater or less part 20 into the auxiliary piping system 54, 56 and 15. When the sprinkler is normally set for use, the entrance opening 58 is closed by a valve 59 which may be held by the same strut 53 which holds the valve 52 closing 25 the base or discharge orifice of the sprinkler; but when the sprinkler goes into action in a normal way this valve is cleared away by the fusing and dissolution of the strut. If it should happen that the parts 30 do not clear themselves promptly, that result is assured by the presence of a fin 57 set eccentrically on the valve 59 so that the valve will be knocked away by the unbalanced impact of the jet of fluid upon it.

35 The auxiliary piping system 15, which is preferably of small diameter, extends to the region of the dry pipe valve, where it runs to one side of a diaphragm 60 which normally may be pressed toward it by a stem 40 61 impelled by a spiral spring 62, or other convenient means of known strength, and when in this position is engaged with the tail of a latch lever 64 whose other end is the latch 40, the lever itself being pivoted 45 at 63 in a flexible rubber stopper. These parts are assembled, so that when the diaphragm is shifted from its illustrated position, where it is bulged upward by the spring 62, and is pushed downward by an impulse of air reaching it through the auxiliary piping 15, the outside tail of the latch lever 64 is swung downward, lifting the latch 40 and thus releasing the weight, which falls, and by its lever throws up the 55 valve 32, opening the drain 30. Immediately, relaxation of pressure on the larger side of the dry pipe valve follows; the water pressure in the supply throws that valve open; and water rushes from the supply 10, 23 through intermediate chamber 25 into the distribution system 13 and to the particular sprinkler 14 which is discharging. This is the normal operation as an automatic fire extinguisher.

55 The automatic security of the system

against being set off so as to discharge water when there is not a fire results from the fact that the mere escape of air from the distribution system 13, through opening of a sprinkler, leakage, or otherwise, does not 70 cause the operation of the dry pipe valve. Such escape merely reduces pressure in the intermediate chamber 25; and it is immaterial in apparatus of this invention whether the pressure falls slowly or rapidly, for so 75 long as it falls it merely increases the margin of safety by which the water clapper 21 is pressed upon its seat by the differential clapper 22.

In order that there should be normal operation, the nozzle from which the jet of air issues at the sprinkler head must be in its alignment with the opening in the yoke which constitutes the target and both must be open and free and clear. If the yoke 80 receives a blow so as to knock it awry and cause leakage from the sprinkler head, without the valve 52 being knocked out, the presence of the valve body prevents the jet from striking the target hole 58, sending it off 85 sidewise; and also the presence of the valve 59 is an additional safe-guard, preventing the jet from entering even if it should strike. If the whole head is knocked off, as sometimes happens, the issuing jet from 90 the wide open nozzle 50 does not get underway until the target opening 58 is entirely out of its path, so that no impulse is transmitted to the valve. In either case, however, an ordinary pressure gauge (not 95 illustrated) on the distribution system will 100 give warning by showing the reduction of pressure.

In operation of the particular embodiment of the invention shown in the drawings, the dry pipe valve, when set, is held closed by the greater total pressure of the supply water on its large than on its small 105 clapper, and will continue so closed until this water pressure differential is upset by 110 reduction of pressure on the larger clapper. The mere escape of air from the sprinkler system and intermediate chamber, as through a bent or broken sprinkler head, will not 115 alone cause the valve to open; but there must also be an impact of the jet of air from the sprinkler nozzle upon its target opening 58 with consequent transmittal of an operating signal to the dry pipe valve, through the auxiliary piping system 54, 56, 15. 120 When a normal opening of a sprinkler occurs, as upon the melting of the strut 53 followed by the clearing away of the valves 52 and 59, such an impact occurs, as the jet enters the opening 58 and sets up a pressure impulse which is transmitted by the air in the auxiliary piping 15 to the diaphragm 60. The latter flexes downward, pushing the stem 61 ahead of it, and thereby tilting 125 the latch lever 64 to disengage it from the 130

weighted lever 36. This lever, now free, is swung about its pivot by the weight 38, until its short arm knocks the valve 32 from its seat, thereby clearing the open drain 5 from the actuator chamber 12 to the intermediate chamber 25. Water thereupon flows through the open drain faster than it can enter the actuator chamber through the pipe 27, because of the restriction 29. As a

10 result the pressure on the larger or differential clapper 22 rapidly diminishes in intensity until its total pressure is less than the pressure on the water clapper 21, whereupon the latter is lifted and the water supply 15 rushes through the intermediate chamber into the distribution piping and thence to the open sprinkler heads, to be discharged.

The apparatus thus described may be said 20 in broad terms to disclose means for transmitting, from a sprinkler head to the dry pipe valve actuating device, a signal showing that a target has been touched by the jet from the sprinkler head. Obviously the 25 invention is not limited to the particular signalling means, here illustrated, as means for receiving and transmitting a puff of air through a tube to the dry pipe valve; nor to the particular type of actuator here 30 illustrated, in which a sudden release of water pressure is effected by receipt of an air impulse from the operating sprinkler head, nor is it limited to differential valves, or to operation by causing a release of water 35 pressure, for other types of dry pipe valves and methods of releasing them are known which might be actuated by the receipt of an operating signal resulting from the touching of the target by the sprinkler jet.

I claim as my invention:

40 1. A fire extinguisher sprinkler system comprising distribution piping having jet discharging sprinklers with thermally responsive discharge control means, a supply valve adapted to be opened automatically; a target associated with each sprinkler; and means whereby the impact of a jet from the sprinkler on the target opens the supply valve.

50 2. A fire extinguisher sprinkler system comprising distribution piping having contents under pressure and sprinklers with thermally responsive discharge control means, a supply valve adapted to remain closed notwithstanding diminution of pressure in the distributing system, said valve being adapted to be opened automatically; and means whereby the impulse of said pressure contents, issuing from a normal opening of a sprinkler, is effective to open 55 said valve.

60 3. A fire extinguisher sprinkler system comprising distribution piping having jet discharging sprinklers with thermally responsive discharge control means, a supply valve adapted to remain closed notwithstanding

standing diminution of pressure in the distributing system, said valve being adapted to be opened automatically; and means to open said valve including a target associated with each sprinkler in position to be hit by a normal jet therefrom.

4. A fire extinguisher sprinkler system comprising distribution piping having sprinklers with thermally responsive discharge control means, a supply valve adapted to remain closed notwithstanding diminution of pressure in the distributing system, said valve being adapted to be opened automatically; and means independent of said piping to communicate operatively to the supply valve an impulse from the normal discharge of a sprinkler head, thereby to effect said automatic opening.

5. A fire extinguisher sprinkler system comprising distribution piping having sprinklers with thermally responsive discharge control means, a supply valve adapted to remain closed notwithstanding diminution of pressure in the distributing system, said valve being adapted to be opened automatically; and means including a tubular connection from each sprinkler head to the supply valve, adapted to receive a jet normally discharged from such sprinkler head and to transmit the impulse thereof to the supply valve, thereby to open it.

6. A fire extinguisher sprinkler system comprising distribution piping having sprinklers with thermally responsive discharge control means, a supply valve adapted to remain closed notwithstanding diminution of pressure in the distributing system, said valve being adapted to be opened automatically; and means comprising a line of tubing extending past the sprinklers in the system to the region of the supply valve and normally closed at each sprinkler, but adapted to be opened by the normal thermally controlled discharge action of the sprinkler; and means whereby the impulse thus transmitted effects opening of the supply valve.

7. A fire extinguisher sprinkler system comprising distribution piping having a fluid under pressure and sprinklers with thermally responsive discharge control means, a supply valve therefor adapted to be opened automatically, arranged and adapted to remain closed notwithstanding diminution of pressure in the distributing system; and communication means independent of the distributing system to effect said automatic opening upon the normal opening of a sprinkler.

8. A fire extinguisher sprinkler system comprising distribution piping having sprinklers with thermally responsive discharge control means; a supply valve therefor adapted to be held closed by the supply pressure; communication means from the sprinklers to the supply valve, independent

- of the distribution system and means whereby the normal opening of the sprinkler head impresses thereon an impulse which effects said automatic opening of the supply valve.
- 6 9. A fire extinguisher sprinkler system comprising distribution piping having sprinklers with thermally responsive discharge control means; a supply valve and an actuator therefor adapted to operate upon 70 being subjected to pressure; a fluid under pressure in the distribution piping; and means for conveying pressure to said actuator from the discharge of said fluid upon the normal opening of a sprinkler.
- 10 15. 10. A fire extinguisher sprinkler system comprising distribution piping having sprinklers with thermally responsive discharge control means; a supply valve therefor adapted to be closed by the supply pressure 75 comprising a differential valve in which the supply fluid communicates through a restricted opening with the larger clapper of the valve, opposing opening of the valve; combined with a less restricted drain from said opposing body of fluid; and means actuated by normal operation of a sprinkler head to open the said drain.
- 20 11. A fire extinguisher sprinkler system comprising distribution piping having 80 sprinklers with thermally responsive discharge control means; a supply valve therefor adapted to be closed by the supply pressure comprising a differential valve in which the supply fluid communicates through a restricted opening with the larger clapper of the valve, opposing opening of the valve; said distributing system being open to and supplied through the intermediate chamber of said valve; and means independent of 85 pressure in the intermediate chamber to open the supply valve upon the normal opening of a sprinkler head.
- 25 12. A fire extinguisher sprinkler system comprising distribution piping having 90 sprinklers with thermally responsive discharge control means; a supply valve therefor adapted to be closed by the supply pressure comprising a differential valve in which the supply fluid communicates through a restricted opening with the larger clapper of the valve, opposing opening of the valve; said distributing system being open to and supplied through the intermediate chamber of said valve, and means to relieve the pressure on said opposing clapper upon the normal opening of a sprinkler head.
- 30 13. A fire extinguisher sprinkler system comprising distribution piping having 95 sprinklers with thermally responsive discharge control means; a supply valve; a pressure chamber, the fluid pressure in which normally holds the supply valve closed; means tending to relieve the pressure in said chamber; restraining means for the said restraining means and means actuated by normal 100 pressure in the distribution system to release the supply valve; and means arranged to coact with the normal sprinkler discharge from the distribution system to release the pressure on the larger clapper of the supply valve.
- 35 14. A fire extinguisher sprinkler system comprising distribution piping having 105 sprinklers with thermally responsive discharge control means; a supply valve and means which normally holds the supply valve closed; means adapted to be actuated by a pulsation to release the supply valve; and means other than the distribution piping adapted to receive and transmit thereto a pulsation resulting from normal opening of a sprinkler.
- 40 15. A distribution system with sprinklers and a supply valve; means whereby the supply valve is normally held closed; control means for releasing it; a latch restraining 110 said control means; a diaphragm connected with said latch; and communication means arranged along the distribution system and adapted to convey a pressure impulse to said diaphragm upon normal opening of a sprinkler, for causing release of said latch and consequent opening of the supply valve.
- 45 16. A distribution system having fluid under pressure therein, with sprinklers and a differential supply valve; a chamber separate from the distribution system, 115 adapted to contain fluid whose pressure on the larger clapper of said valve maintains it closed; and means whereby normal discharge of the fluid in the distribution system vents said fluid which is pressing on the larger clapper of the differential valve.
- 50 17. A distribution system having sprinklers and a differential supply valve held closed by pressure on the larger clapper; means to relieve said pressure on the larger clapper to effect its opening; comprising a vent, therefor and means responsive to a pressure pulse to open the vent.
- 55 18. A distribution system having sprinklers and a differential supply valve held 120 closed by pressure on its larger clapper, the distribution system being connected with the intermediate chamber of the supply valve, whereby mere diminution of pressure in the distribution system does not release the supply valve; and means arranged to coact with the normal sprinkler discharge from the distribution system to release the pressure on the larger clapper of the supply valve.
- 60 19. A distribution system having a supply valve arranged to be held closed normally; a chamber having a movable wall and connections adapted to release said holding of the supply valve; the said chamber normally containing air at low pressure, and there being air at higher pressure in the distribution system; and connections whereby a discharge of air occurring normally from the distribution system through 125
- 65 130

- a sprinkler raises the air pressure in said chamber thereby moving said wall to release the supply valve.
20. A distribution system with sprinklers and a supply valve; means whereby the supply valve is normally held closed; control means for releasing it; a trigger restraining said control means; means for moving said trigger adapted to be actuated by an impulse; and communication means arranged along the distribution system and adapted to convey an actuating impulse to said trigger resulting from the normal opening of a sprinkler in the distribution system.
- 15 21. A distribution system with sprinklers and a supply valve; means including a local chamber containing fluid under pressure whereby the supply valve is normally held closed; control means for releasing said fluid from the local chamber; and communication means arranged along the distribution system and adapted to convey an actuating impulse to said control means resulting from the normal opening of a sprinkler in the distribution system.
- 20 22. A distribution system with sprinklers and a differential supply valve; a local chamber containing fluid under pressure whereby the supply valve is normally held closed; said chamber having a supply through a restricted opening normally maintaining the pressure and having a less restricted drain which releases the fluid more quickly than the restricted opening can supply it; and means actuated by impulse from normal discharge of a sprinkler, for opening said drain.
- 25 23. A fire extinguisher sprinkler system comprising distribution piping; a supply valve therefor; a sprinkler attached thereto having thermally responsive discharge control means; means to receive and transmit an impulse caused by its normal opening; and means responsive to said impulse whereby the said supply valve is actuated; said impulse receiving means being adapted to be displaced by a distortion of the shape of the sprinkler, so as not to receive an impulse from a distorted sprinkler.
- 30 24. A fire extinguisher sprinkler system comprising distribution piping; a supply valve therefor; a sprinkler attached thereto having thermally responsive discharge control means and having a tubular yoke with opening in alignment with the nozzle of the sprinkler, whereby a jet issuing from the nozzle may impress an impulse within said yoke; transmitting means; and means responsive to said impulse for actuating the supply valve.
- 35 25. A fire extinguisher sprinkler system comprising distribution piping; a supply valve therefor; a sprinkler attached thereto having thermally responsive discharge control means and having a tubular yoke with

- opening in alignment with the nozzle of the sprinkler, said yoke being normally closed by the said control means, and adapted to be opened by the removal of said control means, whereby the jet from the nozzle may enter its said opening and cause a pressure impulse in the yoke; transmission means; and means responsive to said impulse for actuating the supply valve.
- 40 26. A fire extinguisher sprinkler system comprising distribution piping; a supply valve therefor; a sprinkler attached thereto having thermally responsive discharge control means and having an auxiliary passage with a hole in alignment with its nozzle and normally closed by its said control means, and adapted to be opened by the removal of said control means, whereby the jet from the nozzle may enter the said hole and produce a pressure impulse; and means for transmitting said impulse to cause opening of said supply valve.
- 45 27. A fire extinguisher sprinkler system comprising distribution piping; a supply valve therefor; a sprinkler attached thereto having thermally responsive discharge means and comprising a tubular yoke having an entrance in alignment with the discharge orifice; a valve normally closing said entrance and having a vane in position to be struck by a jet issuing from said orifice, whereby the valve is dislodged, and the entrance opened, and the jet creates a pressure impulse in the yoke; and means for transmitting said impulse to cause actuation of the supply valve.
- 50 28. A fire extinguisher sprinkler system comprising distribution piping; a supply valve therefor; actuating apparatus for control of said supply valve; sprinklers attached to said piping, said sprinklers including means for receiving and transmitting the impulse caused by normal sprinkler discharge of fluid; and means for transmitting said impulse to said actuating apparatus, whereby the latter opens said supply valve.
- 55 29. A fire extinguisher sprinkler system comprising a dry pipe valve; an actuator therefor; sprinklers with thermally responsive discharge control means; and a double system of piping connected to said sprinklers, through one of which systems the fire extinguishing liquid may be transmitted from the dry pipe valve to the sprinklers, and through the other of which a pressure impulse may be transmitted to the actuator to cause opening of said valve; the said sprinklers being adapted to receive and transmit said impulse upon normal discharge.
- 60 30. A fire extinguisher sprinkler system comprising distribution piping having sprinklers with thermally responsive discharge control means; a supply valve; an actuator therefor; and an auxiliary system

of piping connecting said actuator and said sprinklers; there being a target associated with each sprinkler and constituting an inlet to said auxiliary piping, whereby upon normal discharge of a sprinkler a pressure impulse enters said inlet and is transmitted by said auxiliary piping to said actuator, to effect opening of the supply valve.

31. A fire extinguisher sprinkler system comprising distribution piping with sprinklers; a supply valve; an actuator therefor; and an auxiliary system of piping connecting said actuator and said sprinklers; said

sprinklers having a discharge opening for said distribution piping, and having an inlet opening to said auxiliary piping; a thermally responsive strut closing both openings and adapted upon displacement to open both openings, whereupon the flow from said discharge opening causes an impulse to enter said inlet opening and traverse said auxiliary piping to the actuator, thereby effecting opening of the supply valve.

Signed at Providence, Rhode Island, this thirteenth day of October, 1922.

ALBERT J. LOEPSINGER.
